Attorney,

UNITED STATES PATENT OFFICE.

HARRY W. SMITH, OF PAWTUCKET, RHODE ISLAND, ASSIGNOR TO NICKERSON ART METAL COMPANY, OF PROVIDENCE, RHODE ISLAND, A CORPORATION OF RHODE ISLAND.

WIRE-FORMING MACHINE.

1,267,132.

Specification of Letters Patent. Patented May 21, 1918.

Application filed April 24, 1917. Serial No. 164,128.

To all whom it may concern:

Be it known that I, HARRY W. SMITH, a citizen of the United States, and resident of the city of Pawtucket, in the county of 5 Providence and State of Rhode Island, have invented certain new and useful Improvements in Wire-Forming Machines, of which the following is a specification.

This invention relates to machines for 10 automatically making rings or wire and applying them to different pieces of work.

The object of this invention is to provide 15 a set of wire bending or forming devices in the machine, and means for feeding wire to these formers and severing the wire into short lengths; and also to provide means for supporting individual pieces of work in the path of movement of said formers, whereby the formers are caused to bend the 20 cut lengths of wire about the work.

A further object of the invention is to provide a magazine in which the work is stored, and means operated by the action of the machine for feeding the pieces of 25 work into position to have the wire bent and formed about the same.

The work herein illustrated is in the form 30 of a short post having a reduced neck portion around which is formed a ring of wire by the action of the machine, which ring in this particular case forms a spring lock 35 on the post, but work of any suitable shape or size may be fed to the machine and supplied with pieces of wire bent into the desired form by wire forming mechanism.

With these and other objects in view, the invention consists of certain novel features of construction, as will be more fully described, and particularly pointed out in the 40 appended claims.

In the accompanying drawings:

Figure 1— is a plan view of the machine. Fig. 2— represents a section on line 2—2 of Fig. 1 on a larger scale, some parts being 45 omitted and other parts being broken away to better illustrate the wire forming and cutting mechanism.

Fig. 3— is a front view of the work feeding mechanism showing the rest bar as 50 positioning the work to have the wire bent about its neck portion.

Fig. 4— is the same as Fig. 3 but with the rest bar withdrawn to permit the finished work to drop away by gravity, and 55 also showing the next adjacent piece of

work as retained in position until the rest bar is repositioned to receive it.

Fig. 5— is a top view of the work feed mechanism.

Fig. 6— is a sectional plan view on line 60 6—6 of Fig. 2 illustrating the operation of the wire formers and showing the wire as having been fed into position to be bent.

Fig. 7— shows the severed piece of wire 65 as bent into a U-shape in one of the formers.

Fig. 8— shows the U shaped wire as having been carried forward to engage the neck of the work.

Fig. 9— shows the wire as bent into a 70 ring formed about the neck of the work.

Fig. 10— is a detail showing one form of work to which the wire may be attached by my wire bending and attaching machine.

The main bed or table 30 of the machine is provided with suitable standards, and has 75 journaled bearings 31 for three shafts 32, 33 and 34. The shaft 32 is provided with fast and loose pulleys 35 and 36, the fast pulley having a crank or handle 37 to enable the machine to be operated by hand 80 when desired. The shafts are geared together by miter gears 38 and 39 to run in unison. The wire *a* is fed to the machine from the roll 40 and is fed forward intermittently by action of the cam 41 on shaft 85 34 through the arm 42 through the suitable feed blocks 43, the wire *a* being fed through the guide 44 illustrated in Fig. 6 to abut against the stop 45 which determines the length to be cut. After the wire has been 90

thus fed by action of the feeder the same is severed at the point 46 in Fig. 6 by the cutter 47, see Fig. 2, which cutter is pivoted at 48 and is actuated by the inward movement of lever 49 by contact of cam 50 with roll 95 51, which causes pin 52 to ride inward under the beveled end 53 of this cutter lever, a spring 54 returning the lever after action. Rigidly secured to or integral with the wall members 55 and 56 of the block 57 are two cheek pieces 58 having grooves 59 opposite each other as shown in Fig. 6. After the length of wire has been cut off and occupies the position shown in Fig. 6 the severed piece is bent into U-form and carried into the outer ends of the grooves 59 by the binding pin 60, which constitutes the outer end of an arm rigidly secured to a rock shaft 61, see Fig. 2, said rock shaft has also secured to it a bifurcated arm 62, the slot or recess of

said arm being engaged by a pin 63 in the slide bar 64. The other end of this bar carries a roll 65 which engages a cam groove 66 formed in one side of the disk 70 which is secured to shaft 34 so that as said shaft rotates the bending pin 60 may be carried from the position indicated in Fig. 6 to the position indicated in Fig. 7 and then returned. When the parts are in position shown in Fig. 7 the curved portion of the wire is carried into a groove 71 in the end of the pusher or front former 72, which is rigidly secured to or integral with the slide 73 mounted to reciprocate in a suitable guide that is formed in one of the fixed blocks, the outer end of this slide 73 having a roll 74, which engages a cam groove 75 in the disk 75^a carried by shaft 34.

When the wire is pushed by the feed device through the bushing 44 and is cut off, the severed length is carried down behind to pins 76, which rise from the upper face of the bifurcated slide 77, see Figs. 2 and 6.

When the wire is first cut off the slide 77 is in its lower position, which position is somewhat exaggerated in Fig. 2, and then the said slide 77 is lifted to carry the wire to the horizontal plane of the grooves 59 of the cheek pieces 58, said slide 77 is moved in a suitable guideway that is in the block 57 and the slide is cut out at 78 to receive the cross pieces 79 which are secured to said block 57. The inner faces of the two inner arms or members of the slide 77, near their upper ends, are provided with positioning grooves 80 which are adapted to register with the grooves 59 when the slide 77 is in its uppermost position, the purpose of said grooves being presently explained.

40 The slide 77 is provided with a lateral pin 81 which is engaged by the slotted end of lever 82 pivoted at 83 and having a roll 84 which is engaged by a cam 85 projecting from the disk 70. A spring 86 is suitably connected to this lever 82 to return the same to normal after having been actuated by cam 85.

After the cut piece of wire has been positioned as shown in Fig. 7, the timing of the parts of the machine is such that the bending pin 60 next swings outwardly to position so that its upper end is below the horizontal plane of the grooves 80, this outer and lower position of the pin 60 being best indicated in Fig. 2. The slide 73 is then actuated so that the pusher or front former 72 acts upon the U-shape piece of wire to slide it along and out of the grooves 59 into the grooves 80 in the inner faces of the two arms of the vertical slide 77, the U shape piece of wire being thus transferred to the position shown in Fig. 8, the two legs of the U-shaped piece of wire straddle the post or neck of the work 87, presently described, 65 and reaching the ends of the curved hori-

zontal groove 88 formed in the front end of the back former 89, which at this time, has been advanced from the position shown in Figs. 6 and 7 to the position shown in Fig. 8. This back former 89 is carried by a slide 90, see Fig. 2, mounted in a guide-way therefor in the upper end of a rigid standard or post 91. The rear end of this slide extends through the bearing 92 and is provided with an adjustable head 93 on its outer end arranged to contact with the cam 94 fixed to shaft 32.

During the movement of the parts from the position indicated in Fig. 7 to that indicated in Fig. 9 the opposite ends of the front former 72 and the back former 89 are brought nearly together closing the ring about the neck of the work.

In order to position the work in the path of action of the wire formers 72 and 89 so that a ring of wire 94 may be formed about it, I have provided an elongated vertically disposed tube 95 through which the work is fed. This tube is supported on the upright face of the angle plate 97 to which it is held by means of the clamp 98, see Fig. 5. A hole 99 is formed in the side wall of this tube through which the end of a longitudinally slidable bar 100 is adapted to extend to reach into the tube and engage the work to hold the same, for the purpose presently described. This bar is arranged to slide in a groove formed on the face of the angle plate and is normally pressed inward by means of the spring 101. This bar is provided with a downwardly extending finger 102.

In order to support the work in line of action of the formers a longitudinally slidable rest bar 103 has its inner end 104 arranged to extend beneath the work, see Fig. 3, its body portion being slidably mounted in the bearing 104 and its outer end is provided with a roll 105 resting against the operating cam 106 mounted on the shaft 33. The roll is normally held back against the cam under tension of the spring 107. The forward end of this bar is provided with an angular notch 108 against which the inwardly turned end 109 of the lever 110 rests, this lever being pivoted at 111 to the angle plate 96. The upper end 112 of this lever engages the finger 102, whereby when the rest bar is carried forward by action of the cam 106 beneath the work, the lever 110 withdraws the retaining bar from engagement with the work, permitting the work to be fed down by gravity until the lowermost piece rests upon the end of the bar, which positions the neck portion 113 of the work in alignment to have the ring 94 bent around it. As soon as the ring-forming operation is completed this rest is allowed by the cam to be withdrawn under action of spring 107, which withdrawing action

permits the retaining bar to simultaneously move inward and grip the work piece next above and retain it and the others resting upon it until the lowermost and finished 5 work drops away by gravity through the opening 114 in the bed plate 30.

In some cases, it is found desirable to provide a magazine for carrying large quantities of the work pieces so that the rapidly 10 running machine may be fed continuously. To accomplish this, I have provided an auxiliary tube 115, which may be of any desired length, the same being enlarged on its lower end 116 to fit over the short tubing 95 and 15 which long tubing member is filled with the work and then attached in position to the short tubing 95 and when this magazine tube has been emptied it may be removed and a duplicate loading tube positioned to take its 20 place. In this way the continuity of operating the machine may be undisturbed.

I have shown and described the work piece as being in the form of a short cylindrical member or post but the work to which 25 the bending wire is applied may be of any suitable shape and any suitable means may be provided for supplying and positioning this work relative to the ring-forming mechanism for the purpose of applying the rings 30 thereto.

I have illustrated one means whereby my invention may be carried out, but I do not wish to limit myself to this specific construction as various changes in shape and 35 form of the several features may be necessary. I, therefore, desire it to be understood that I reserve the privilege of resorting to all the mechanical changes to which the device is clearly susceptible, the invention be- 40 ing defined by the appended claims.

I claim:

1. In a machine of the character described,

wire formers, means for feeding wire to said formers and severing the same into lengths, means for supporting individual pieces of 45 the work in the path of movement of said formers, means whereby said formers are caused to bend the cut length about the work, means for withdrawing said supporting means to permit the work to be discharged, and means for feeding a fresh piece of work to be operated upon.

2. In a machine of the character described, wire formers, means for feeding wire to said formers and severing the same into lengths, 55 a magazine for supplying the work, means for supporting each individual piece of the work in the path of movement of said formers, means whereby said formers are caused to bend the cut length about the work, 60 means for withdrawing the support from the finished work permitting it to be discharged, and means for feeding a fresh piece of work from the magazine to be operated upon. 65

3. In a machine of the character described, wire formers, means for feeding wire to said formers and severing the same into lengths, a magazine for supplying the work, a rest bar for supporting the work in the path 70 of said formers, means whereby said formers are caused to bend the cut length of wire about the work, means for withdrawing the rest bar to permit the finished work to be discharged, and means operated by the 75 withdrawing action of said bar for retaining the next adjacent piece of work until said rest bar is repositioned to receive the work.

In testimony whereof I affix my signature 80 in presence of a witness.

HARRY W. SMITH.

Witness:

HOWARD E. BARLOW.
